(57) **CLAIM**

The ornamental design for the combined window frame lineal and cap, as shown and described.

DESCRIPTION

FIG. 1 is an upper right perspective view of the combined window frame lineal and cap, according to the design;

FIG. 2 is a front view thereof;

FIG. 3 is a rear view thereof;

FIG. 4 is right side view thereof;

FIG. 5 is left side view thereof;

FIG. 6 is a top view thereof; and,

FIG. 7 is a bottom view thereof.

The combined window frame lineal and cap is shown with a symbolic break in its length. The appearance of any portion of the combined window frame lineal and cap between the break lines forms no part of the claimed design.
